UNITED STATES PATENT OFFICE.

JOHN PATRONELL, OF ORANGE, TEXAS.

SAFETY-CAN.

1,315,033.

Specification of Letters Patent.

Patented Sept. 2, 1919.

Application filed June 1, 1918. Serial No. 237,712.

To all whom it may concern:

Be it known that I, JOHN PATRONELL, a citizen of the United States, residing at Orange, in the county of Orange and State of Texas, have invented new and useful Improvements in Safety-Cans, of which the following is a specification.

The object of the invention is to provide a can or similar receptacle with a cover or closing means adapted to be firmly locked in position to constitute a practically air-tight closure, while permitting the ready removal of said cover when desired, without in any way detracting from the utility of the can or rendering the same unfit for subsequent use for the original or any analogous purpose, and to this end the invention consists in the certain construction, combination and relation of parts hereinafter fully set forth, it being understood that changes in form, proportion and details may be resorted to without departing from the spirit of the invention.

In the drawing,

Figure 1 is a side view partly broken away of the receptacle having a cover constructed with a fastening device in accordance with the invention.

Fig. 2 is a vertical sectional view of the same.

Fig. 3 is a similar view showing the cover disengaged and elevated.

Fig. 4 is a detail view of one of the locking elements.

Fig. 5 is a horizontal section on the plane indicated by the line 5—5 of Fig. 2.

In the illustrated embodiment of the invention the can proper or receptacle 10 is provided interiorly with transverse or horizontal rings or ledges 11 and 12 spaced apart and providing respectively lower and upper shoulders, it being obvious that said rings may be provided either by attachment to the inner surface of the receptacle or by heading the wall of the latter, as both methods are well known in the manufacture of receptacles of various types.

Removably fitted in the top of the receptacle and normally seated at its lower edge against the upper ring 11 is a sleeve 13 which is preferably tapered or reduced slightly toward its lower edge and is provided at its upper edge with an inturned flange 14 forming a stop for co-operation with an outturned flange 15 which is formed on the lower edge of the rim 16 of the can

top or cover 17. The disk 18 which constitutes the closure supporting the flange 16 is of a diameter in excess of the latter so as to form a bearing upon the upper edge of the receptacle as shown clearly in Fig. 2.

Carried by the flange of the top or cover is a ring 19 with which are connected links 20 carrying shoes 21 of segmental form and adapted when folded to lie in close contact with the surface of the flange, so that the top or cover with its flange and attached shoes may be withdrawn through the opening formed by the ring 11 and raised until the flange 15 comes in contact with the flange 14 or stop 14 on the sleeve 13 to avoid separation of said top or cover and sleeve.

The depth of the flange 16 is such that when the top or cover is in its closed position the shoes 21 are interlocked with the ring 12, and the adjacent surfaces of said shoes and the shoulder formed by the ring 12 are serrated so that when the top or cover has been inserted and is turned slightly the engagement of the serrated surfaces will serve to hold the shoes against rotary movement with the top or cover and will cause the links 20 to swing outward to assume a position substantially radially of the top or cover and hence lock the latter in place. The positioning of the shoes between the shoulders formed by the adjacent surfaces of the rings 11 and 12 constitutes a break-joint and a swinging movement of the links beyond an approximately radial position is prevented by shoulders or stops 22 on the ring 19, a sufficient swinging movement however being permitted to constitute an eccentric arc. In other words the rings are permitted to swing under the turning movement in one direction in the turning of the top or cover so as to pass beyond the center a sufficient distance to hold them in place and thus avoid the possibility of accidental disengagement and release of the top or cover. On the other hand when it is desired to remove the cover it is only necessary to turn the same in the opposite direction from that above described in order to permit the links to swing in the reverse direction, sliding movement of the shoes being prevented by the interlocking motion of the same and the shoulder 12, whereupon the lid or cover may be elevated until its flange 15 comes in contact with the stop 14 on the sleeve 13.

By a continued outward movement of the cover it will be understood that the entire cover

structure including the sleeve 13 may be removed from the receptacle, thus exposing the interior of the can for the removal of its contents. The function of the tapering sleeve 13 is to form a guide for the downward movement of the cover, so that said cover will be seen in its downward movement, the flange 15 riding in contact with said sleeve so that it will properly clear the ring 11 in the operation of closing the cover and interlocking the same with the ring 12. Also, the sleeve 13 forms a sealing medium to reduce evaporation of the contents of the can and entrance of dirt or dust thereto when the cover is partially withdrawn, as shown in Fig. 3, and further coöperates with the disk 18 to seal the joint between the same and the upper edge of the can for the same purposes when the cover is fully applied, as shown in Figs. 1 and 2.

Obviously with a construction such as described the opening of the can or receptacle can be accomplished without mutilating either the body of the receptacle or the cover and when the latter has been seated a slight turning movement thereof, as to the left, will insure a firm locking of the same against further movement in the same direction and the opening of the can except by the course above noted which consists in turning the lid or cover in the opposite direction so as to cause the release of the shoes or the disengagement thereof from the interior shoulders of the receptacle to allow the raising thereof.

Having thus fully described my invention, I claim:—

1. A receptacle having interior facing shoulders and a lid or cover having a depending flange or rim, shoes arranged between said shoulders, and links for connecting the shoes with the flange or rim of the lid or cover.
2. The combination with a receptacle having an interior serrated shoulder, of a lid or cover having a depending flange or rim, shoes for arrangement in contact with said shoulder of the receptacle, and a link con-

nection between the shoes and the flange or rim of the lid or cover.

3. The combination with a receptacle provided with interior spaced shoulders, of a lid or cover having a depending interior flange or rim, segmental shoes for arrangement between the planes of said shoulders of the receptacle, links connecting said shoes with the flange or rim of the lid or cover, and means for limiting the swinging movement of said links.

4. The combination of a can provided with interior spaced shoulders, of a lid or cover provided with an interior depending flange or rim, shoes for arrangement in a plane between said shoulders of the can, adjacent surfaces of the shoes and one of the shoulders being serrated, links for connecting said shoes with the flange or rim of the lid or cover, and means for limiting the swinging movement of said links in one direction.

5. The combination of a receptacle provided with interior spaced rings, a sleeve removably fitted within the receptacle and bearing upon the uppermost ring, a lid or cover having a flange or rim to fit within said sleeve, shoes having a link connection with the flange or rim of the lid or cover and adapted to be arranged in a plane between the said rings of the receptacle, and coöperative stop elements on said sleeve and the flange or rim of the lid or cover.

6. The combination of a receptacle provided with interior upper and lower spaced rings, a sleeve removably seated in the mouth of the receptacle upon the upper ring and provided with an interior flange, a lid or cover having a depending flange or rim to fit within said sleeve and provided with exterior means for engagement with said flange of the sleeve, and shoes having a link connection with the flange or rim of the lid or cover and adapted for arrangement in the space between said upper and lower rings of the receptacle and adapted to be spread by the turning movement of the lid or cover.

In testimony whereof I affix my signature.

JOHN PATRONELL.
